CLAIM

The ornamental design for a sample cartridge, as shown and described.

DESCRIPTION

FIG. 1 is a top perspective view of a sample cartridge, according to a first embodiment;

FIG. 2 is a bottom perspective view of thereof;

FIG. 3 is a top view of thereof;

FIG. 4 is a front view of thereof;

FIG. 5 is a back view of thereof;

FIG. 6 is a right side view of thereof;

FIG. 7 is a left side view of thereof; and

FIG. 8 is a bottom view of thereof;

FIG. 9 is a top perspective view of a sample cartridge, according to a second embodiment;

FIG. 10 is a bottom perspective view of thereof;

FIG. 11 is a top view of thereof;

FIG. 12 is a front view of thereof;

FIG. 13 is a back view of thereof;

FIG. 14 is a right side view of thereof;

FIG. 15 is a left side view of thereof; and,

FIG. 16 is a bottom view of thereof.

The dot-dash lines in the drawings depict the boundaries of the claim and form no part thereof.

The dash lines in the drawings depict portions of the sample cartridge that form no part of the claimed design.
